UNITED STATES PATENT OFFICE.

CLAUDE R. CRAIG, OF WYMORE, NEBRASKA.

RAILWAY-LANTERN.

1,370,092.

Specification of Letters Patent.

Patented Mar. 1, 1921.

Application filed October 19, 1920. Serial No. 417,993.

To all whom it may concern:

Be it known that I, CLAUDE R. CRAIG, a citizen of the United States, residing at Wy-
more, in the county of Gage and State of
Nebraska, have invented a new and useful
5 Railway-Lantern, of which the following is
a specification.

This invention relates to railroad lan-
terns, one of its objects being to provide a
10 lantern with means whereby fuses, torpe-
does and matches may be held in convenient
positions where they are protected and can
be easily reached for the purpose of using
them when necessary.

15 A further object is to provide containers
of this character which can be combined
with a lamp of ordinary construction with-
out making any changes in the lamp struc-
ture.

20 With the foregoing and other objects in
view, which will appear as the description
proceeds, the invention resides in the com-
bination and arrangement of parts and in
the details of construction hereinafter de-
25 scribed and claimed, it being understood
that, within the scope of what is claimed,
changes in the precise embodiment of the
invention shown can be made without de-
parting from the spirit of the invention.

30 In the accompanying drawings the pre-
ferred form of the invention has been
shown.

In said drawings

Figure 1 is an elevation of a lamp having
35 the present improvements combined there-
with.

Fig. 2 is a plan view.

Referring to the figures by characters of
reference 1 designates a lantern of ordinary
40 construction provided with the usual wire
cage 2 having a base ring 3 and an interme-
diate side ring 4. The attachments making
up the present invention are adapted to be
mounted on the base ring 3 and to be sol-
45 dered or otherwise secured to it. Mounted
on this base ring at diametrically opposed
points are fusee holders 5 arranged in pairs
and each of which is in the form of an elon-
gated cylindrical container, the containers
50 of each pair being arranged side by side and
secured together throughout their length.

These fusee holders or containers are not
only secured to the base ring 3 but are also
soldered or otherwise fastened to the inter-
mediate ring 4. Thus they are supported 55
in inclined positions so that the fusee can be
easily placed in or taken from them.

Torpedo boxes indicated at 6 are soldered
or otherwise secured on the base ring 3 at
diametrically opposed points, the outer and 60
inner walls of these boxes being corrugated
as shown so as to provide recesses to receive
the edge portions of the torpedoes and hold
the articles in upstanding positions and out
of contact with each other. Consequently 65
the torpedoes can be easily placed in posi-
tion and can also be readily removed be-
cause by thus spacing them the fingers can
be inserted readily between the torpedoes.

A match box in the form of a short cy-
lindrical container can be soldered or other-
wise secured to the base ring 3 and has a cap
or closure thereon, the said box being indi-
cated at 7 and its closure at 8.

By providing a lantern having the attach-
ments herein described the necessary signal
devices as well as the matches can always
be located readily and are not likely to be-
come misplaced or to be accidentally left on
the car by the trainmen.

It will be noted that while the parts 5 are
primarily used as fusee holders they also
constitute means for reinforcing the cage
which, when in use, is subjected to more or
less rough handling.

What is claimed is:—

The combination with a lantern having a
wire cage including a base ring and an in-
termediate side ring, and fusee holders se-
cured to and constituting reinforcing con-
nections between the rings, of a torpedo box
secured upon the base ring and having op-
posed corrugated walls for receiving the
edge portions of the spaced torpedoes.

In testimony that I claim the foregoing 95
as my own, I have hereto affixed my signa-
ture in the presence of two witnesses.

CLAUDE R. CRAIG.
